WILFRED LEWIS, OF PHILADELPHIA, PENNSYLVANIA, ASSIGNEE, BY MESNE ASSIGNMENTS, TO THE TABOR MANUFACTURING COMPANY, OF PHILADELPHIA, PENNSYLVANIA, A CORPORATION OF PENNSYLVANIA.

MOLDING-MACHINE.

1,121,929.

Specification of Letters Patent. Patented Dec. 22, 1914.

Application filed June 9, 1909, Serial No. 501,133. Renewed July 27, 1912. Serial No. 711,929.

To all whom it may concern:

Be it known that I, WILFRED LEWIS, a citizen of the United States of America, residing in the city and county of Philadelphia, in the State of Pennsylvania, have invented a certain new and useful Improvement in Molding-Machines, of which the following is a true and exact description, reference being had to the accompanying drawings, which form a part thereof.

The present invention relates to molding machines and particularly to the jar molding machines of the kind in which the jar table on which the flask containing the pattern and mold forming material is placed is alternately raised and dropped by the admission to, and exhaust from, the actuating cylinder of the machine of a fluid under pressure such as compressed air.

One object of the present invention is to provide novel mechanism for regulating the admission of compressed air to an exhaust from the actuating cylinder, which is simple and reliable in operation, will give the desired rapidity of reciprocation of the jar table, and will insure against any cushioning of the falling movement of the table.

Another object of the invention is the arrangement of the fluid pressure controlling mechanism which readily permits the operator to count and control the number of times the jar table is raised and dropped at each mold forming operation when he desires to do so, and which also readily permits the operator to regulate the height, if he wishes, to which the jar table is raised preparatory to each jar, and consequently to regulate the force of the blow imparted to the jar table when it is dropped.

The various features of novelty which characterize my invention are pointed out with particularity in the claims annexed to and forming a part of this specification. For a better understanding of the invention however and the advantages possessed by it, reference may be had to the accompanying drawings and descriptive matter in which I have illustrated and described one of the forms in which the invention may be embodied.

Of the drawings: Figure 1 is an elevation, partly in section, of a portion of a jar molding machine and the valve controlling mechanism therefor. Fig. 2 is a sectional eleva-

tion of one of the controlling valves employed. Fig. 3 is an elevation of the apparatus shown in Fig. 1 and taken at right angles to that figure and showing also the controlling valves and piping, and Fig. 4 is a sectional plan of a second controlling valve employed.

In the drawings: A represents the base of the molding machine from which extends upward the vertical stationary piston A'.

B represents the movable cylinder surrounding the piston A' and carrying at its upper end the jar table B' on which the flask, pattern and sand or other mold forming material is placed, the sand being packed about the pattern by jarring the table B'. To obtain this jarring action the cylinder B and the table B' is alternately raised by the admission of compressed air, or other fluid under pressure, to the interior of the cylinder through the port A², and is then dropped when the pressure fluid is exhausted. When the cylinder B drops its lower end B³ strikes against the seat A³ provided for the purpose about the lower end of the piston A'.

A valve casing C is attached to the base member A. The casing C has a chamber C² which registers with the port A² of the base member A. The valve casing C is formed with an inlet chamber C' connected to the chamber C² by a port C⁴, and an exhaust chamber C⁵ connected to the chamber C² by a port C⁶.

A movable valve member D is mounted in the valve casing C and is provided with piston portions D' and D² controlling ports C⁴ and C⁵. When the valve D is up, as shown in Fig. 1, port C⁵ is open and port C⁴ is closed. When the valve D is depressed, as hereinafter described, the port C⁴ is opened and the port C⁵ is closed. Preferably, the piston and ports are so arranged that in an intermediate position of the valve D both the ports C⁴ and C⁵ are closed. The lower end of the valve D passes through the chamber C' and enters a cap C⁸ provided with a cushioning spring D⁴. An escape pipe C⁷ is provided to permit air leaking past the valve into the cap C⁸ to escape freely. The piston D² extends into a chamber D⁶ formed in the valve casing above the chamber C² and the piston D² is of such length that it serves at all times to close communication

- between the chambers C^s and C^e . A spring D^s extending between the upper end of the valve member D and the cap C' , which closes the upper end of the chamber C^e , 5 serves not only to cushion the upward movement of the valve member D , but to normally urge it out of the position shown in Fig. 1 into the position in which the port C^s is closed and the port C^e is open. It 10 should be noted that the pressure in the chamber C' acting on the exposed underside of the piston extension D' urges the valve into the position shown in Fig. 1, in which the port C^s is closed. 15 So far as above described the construction does not materially differ from that described and claimed in my prior Patent No. 891,488, granted June 23rd, 1908, but in the means hereinafter described for operating 20 the valve D , the present invention differs materially from the arrangement of my prior patent. In the arrangement shown in my prior patent, means are provided for positively shifting the valve into the position in which air is exhausted from the jar table cylinder when the latter reaches the upper limit of its movement, and into position to admit the pressure fluid to the jar table cylinder when the jar table drops 25 to its lowermost position. In consequence, with the machine shown in my prior patent the rising and falling movements of the jar table are automatically repeated so long as the supply of the pressure fluid to the inlet 30 port of the valve casing corresponding to the valve casing C herein, is uninterrupted and it is not possible to control the movements of the jar table by controlling the valve corresponding to the valve D herein. 35 While the machine in my prior patent has been used extensively and has been generally satisfactory in operation, I have found that with it there is a tendency sometimes undesirable to cushioning the downward movement of the jar table due to the fact that the controlling valve corresponding to the valve D herein is moved into the position in which it admits compressed air to the operating cylinder before the jar table reaches its 40 lowermost position. I have also found that it is desirable in many cases to provide an arrangement in which the operator has a more direct control over the character and 45 number of blows struck at each jarring operation than is readily possible with the machine of my prior patent. 50 With the present invention the valve D may be moved into and out of the position shown in Fig. 1 by the admission to, and exhaust from the chamber C^e of compressed air, or other fluid under pressure. As 55 shown, the cross sectional area of the piston D' exposed to the downward action of the pressure in chamber C^e is substantially greater than the cross sectional area of pis- 60 ton D' exposed to the upward action of the pressure in chamber C' and in consequence when the pressure in the two chambers are equal valve D moves down from the position shown in Fig. 1. The admission of 70 fluid to and exhaust from the chamber C^e takes place through the pipe H . By reference to Fig. 3 it will be seen that the pipe H leads to the casing of a valve K and this valve may be turned (see Fig. 4) to connect the pipe H with the pipe H' or with the pipe H^s . The pipe H' is connected with the port of a pilot valve L , and the pipe H^s is connected with the pressure fluid supply pipe O . 75 The valve L shown in Fig. 2 comprises a barrel like main casing member L^2 connected at its lower end by the short pipe J' to a pipe J . At some distance above its lower end, the barrel L^2 is provided with a 80 lateral port L^4 and it is to this port that the pipe H' is connected. Below the port L^4 , the barrel L^2 is formed with a valve seat L^3 . A valve member L^5 is located in the barrel L^2 and serves when held against the seat L^3 85 to close communication between the lower end of the barrel L^2 and the port L^4 is normally held against its seat by a spring L^6 and also by the pressure of the fluid in the lower end of the barrel L^2 . A tubular 90 member L^6 works in the upper end of the barrel L^2 and is normally held in the position shown in Fig. 2 by the spring L^7 extending between a shoulder on the barrel L^2 and the cap member L^8 to which the upper 95 end of the tubular member L^6 is connected. Ports L^9 through the wall of the member L^6 above the upper end of the barrel L^2 permit the fluid from the chamber C^e to exhaust 100 through the pipes H and H' , hollow member L^6 and ports L^9 when the member L^6 is in the position shown in Fig. 2, and the valve K is in the position shown in Fig. 4. When the member L^6 is depressed, however, 105 the lower end of the member L^6 first seats 110 on the upper end of the valve member L^5 whereby the bore or passage through the member L^6 is closed. Further downward movement of the member L^6 causes the valve L^5 to be depressed and permits fluid 115 to flow from the pipe J' through the valve L^5 into the pipe H' , and thence through the valve K and pipe H into the chamber C^e of the valve casing C . 120 Means are provided for automatically depressing the member L^6 of the pilot valve L at regular intervals in the operation of the machine. In the form of the apparatus disclosed this means comprises a bell crank lever E keyed to the shaft F' journaled in 125 the bracket F secured to the valve casing C . The two arms E' and E^s of the lever E are alternately engaged as the jar table rises and falls by adjustable stops G' and G^s , respectively, carried on the threaded rod G 130

connected at its lower end to an ear B^2 projecting from the lower end of the cylinder B and connected at its upper end to the table B' . An arm or lug E^3 formed on the 5 ear B^2 extends over the pilot valve L and engages the member L^6 or a threaded extension L^{10} thereof to depress it when the downward movement of the cylinder B brings the stop G' against the lever arm E^2 . 10 On the following upward movement of the cylinder B the stop G' engages the lever arm E' and rocks the lever E to permit the member L^6 of the pilot valve L to return to its original position. Yielding means 15 are provided for holding the lever E against movement except under the positive action of the stops G' and G^2 . In the form shown, a spring F^2 surrounds the pin F' at one side of the bracket F extending between 20 the bracket F and the nut F^4 secured to the end of the bolt. Between the other side of the bracket F and the head F^7 of the bolt, a friction washer F^6 is placed. Of course 25 any other suitable frictional holding means might be employed.

The pipe J' is connected at its lower end to the pipe J, and the latter leads from the chamber C' of the valve casing C to the port of the hand operated valve L' corresponding to the port L^4 . Valve L' is like the pilot valve L in all respects except that 30 preferably it is considerably larger and is manually operated through the hand lever P. The valve casing barrel of the hand operated valve L' is connected to the fluid pressure supply pipe O.

The mechanism described is capable of operation in two ways. In one mode of operation, which is the one more commonly employed, the valve K is turned as shown 40 in Fig. 4 to connect the pipes H and H' . Then when the operator desires to start the jarring operation he depresses the handle P of the hand valve L' , and this serves to 45 connect the pipe J with the fluid pressure supply pipe O. The pipe J then supplies fluid under pressure to the chamber C' of the valve casing C, and to the lower end of the barrel L^2 of the pilot valve L. In the 50 starting position the piston B is down, of course, and consequently valve D closes port C^5 and opens port C^4 , so that the pressure admitted to the chamber C' passes to the chamber C^2 through the ports C^4 and thence 55 through the port A^2 to the space in the cylinder B above the piston A' . This raises the cylinder B and when it reaches the upward limit of its movement the stop G' engages the arm E' of the lever E, and 60 shifts the lever raising the lug E^3 and permitting the member L^6 to rise, whereby the valve member D is moved by the pressure acting on the underside of the piston D' , causing the valve to close the port 65 C^4 and open the port C^5 . This permits the

air to freely exhaust from the cylinder B through the port A^2 , chamber C^2 , port C^5 , chamber C^3 , and waste pipe I, whereupon the cylinder B and table B' drop until their motion is suddenly arrested by the engagement of its lower end B^3 with the seat A^3 . 70 As the cylinder B reaches the lower limit of its movement, and the stop G^2 engages the lever arm E^2 , the lug E^3 engages the member L^6 of the pilot valve L, and moves it 75 into the position in which compressed air is admitted through the pilot valve L to the chamber C^6 to shift valve D, and this operation is repeated so long as the hand operated valve L' is maintained in the position in 80 which it connects the pipes O and J.

Since the movement of the valve member D to close the port C^5 and open the port C^4 follows the operation of the pilot valve L, and the time of the movement is affected by the period required to build up 85 the pressure in the chamber C^6 , the parts can readily be so adjusted that the port C^5 will not be closed, and the port C^4 will not be opened until the cylinder B has completed its downward movement. This avoids 90 all possibility of any cushioning of the drop of the cylinder B by the trapping of air in, or the admission of compressed air to the interior of the cylinder B before the latter 95 has completed its downward movement.

When it is desired to regulate the height to which the cylinder B may be raised on any particular stroke, or to count or control the number of blows struck in forming the 100 mold more closely than can be readily obtained when the valve D is controlled directly by the pilot valve L, a second mode of operation is followed. In the second mode of operation the valve K is turned to 105 the position in which it closes communication between the pipes H and H' , and opens communication between the pipes H and H^2 . When this occurs the pressure of the supply pipe O is continuously maintained 110 in the chamber C^6 of the valve casing C, and the valve D is constantly held in the lowermost position in which the port C^5 is closed and the port C^4 is open. Then, by opening 115 and closing the hand operated valve L' , the pressure fluid is alternately admitted to and exhausted from the cylinder B. With this mode of operation, the operating lever P of the hand valve L' must be depressed for each admission of air to the cylinder B, 120 and must be allowed to rise before the air can thereafter escape from cylinder B. With some classes of work it is desirable to raise and drop the cylinder B only once, twice, or some other small number of times, 125 in forming each mold. With such work, where the reciprocation of the cylinder B is controlled by an automatic valve operated by the movements of the cylinder, it is difficult to control the number of the re- 130

ciprocations of the cylinder as closely as is desired, and of course it is much easier to obtain less than the normal stroke of the cylinder where its movements are controlled solely through the hand operated valve L' than where the control is had both through a hand operated valve and a pilot valve.

As a means for insuring that the upward movement of the cylinder B shall not be sufficient to lift the cylinder off the piston A', I may, as shown, provide the valve D with a stem D⁵ extending upward through the cap C' and through a slot formed for the purpose in the arm E² of the lever E, and to provide this stem at its upper end with a head, for instance the adjustable lock nuts D⁶, which will be engaged by the lever arm E² when the lever E is rocked above the upward normal limit of its motion. This of course results in moving the valve D into the position in which it closes the port C⁴ and opens the port C⁵ regardless of the pressure conditions then existing in the chamber C⁶.

Having now described my invention, what I claim as new and desire to secure by Letters Patent is.

1. The combination with a relatively movable piston and cylinder members of a fluid pressure actuated main valve movable to connect said cylinder member to a source of fluid under pressure or to exhaust to thereby produce relative to and fro movements between said members and fluid pressure operating mechanism for said main valve including a pilot valve mechanism automatically responsive to the relative to and fro movement of said members for shifting said main valve to produce such movements and an alternate manually controlled mechanism for shifting said main valve.

2. The combination with a relatively movable piston and cylinder members of a valve mechanism controlling the admission to and exhaust from said cylinder member of an operating fluid, said valve mechanism including the piston and a chamber therefor, a pilot valve automatically actuated by the relative movements of said members for intermittently connecting said valve mechanism chamber to a source of fluid under pressure or to exhaust to cause the valve mechanism to move in one direction or the other and an alternative mechanism for manually controlling the admission to and exhaust from said cylinder member.

3. The combination with a relatively movable piston and cylinder members with a valve mechanism controlling the admission to and exhaust from said cylinder of an operating fluid, said valve mechanism including a piston and a chamber therefor, a pilot valve for intermittently connecting said valve mechanism chamber to a source of fluid under pressure or to exhaust to

cause the valve mechanism to move in one direction or the other, means for automatically operating the pilot valve when said piston and cylinder members approach the limits of their movement relative to each other and manually controlled means independent of the pilot valve, for controlling the admission to and exhaust from the cylinder of the operating fluid.

4. The combination with the piston and actuating cylinder of a jar molding machine of a valve casing having an inlet chamber and an exhaust chamber, a valve in said casing movable to alternately connect each of said chambers to said cylinder while closing communication between the other chamber and the cylinder, operating mechanism comprising means for moving said valve to and fro in automatic response to the movements of the piston and cylinder relative to each other while constantly supplying fluid under pressure to said inlet chambers and alternative operating mechanism comprising means for holding said valve in the position in which said inlet chamber is connected to said cylinder and manual means for alternately connecting said inlet chamber to a source of fluid under pressure and to exhaust.

5. The combination with the piston and actuating cylinder of a jar molding machine of a valve mechanism including a piston and chamber therefor, said valve mechanism serving to connect said actuating cylinder to an exhaust passage or to another passage according to the pressure in said chamber, mechanism for alternately raising and lowering the pressure in said chamber while maintaining communication between said other passage and a source of fluid pressure and alternative operating mechanism comprising means for maintaining a constant pressure in said chamber and means for connecting said other passage to exhaust or to a source of fluid under pressure at will.

6. The combination with the piston and actuating cylinder of a jar molding machine, of a valve mechanism controlling the admission to and exhaust from said cylinder of an operating fluid, said valve mechanism including a piston and chamber therefor and a pilot valve for intermittently connecting said chamber to a source of fluid under pressure or to exhaust to cause the valve mechanism to move in one direction or the other, and other means independent of said pilot valve responsive to a predetermined relative movement of the first mentioned piston and said actuating cylinder for operating said valve mechanism to cut off the supply of the operating fluid to said actuating cylinder.

7. In machines of the character described, the combination with a piston and a cylinder containing the same and provided with

an intake passage and an exhaust passage for communication therewith, of a valve casing in the path of said intake passage, a valve in said casing arranged to close said intake passage and having a pressure surface of smaller area exposed to the fluid in said intake passage for actuation of the valve and provided with means for closing one of said passages when so actuated, said 10 valve casing having a connection with said intake passage and said valve having an op-

posite pressure face of greater area, and a pilot valve controlled and actuated by the relative movement of the piston and cylinder and the pressure of the intake fluid, said 15 pilot valve being arranged to open said connection and admit fluid to return said valve by pressure on its surface of greater area.
